WINDOW FRAME CONSTRUCTION

Sern Madsen, Clinton, Iowa, assignor to Curtis Companies, Incorporated, Clinton, Iowa, a corporation of Iowa

Application February 23, 1932. Serial No. 594,575

12 Claims. (Cl. 20—11)

An object of my present invention is to provide a frame construction, especially one for a window, having novel characteristics of construction and which may be manufactured inexpensively.

- 5 A further object is to provide a stop on a frame which is limited automatically in its location, so that a minimum dimension may be established between the stop and another one between which a sash, for instance, slides.
- 10 A further object is to provide a jamb with a liner strip which serves the purpose of adapting the frame to different kinds of wall constructions and thicknesses and which so coacts with the jamb that a bead is formed to serve as a limiting 15 means for the position of a stop.

Still a further object is to provide a jamb and a liner strip with their edges rabbeted together, such edges being of different thicknesses whereby to form a shoulder on the inner face of the jamb 20 against which a portion of a stop strip may engage for limiting lateral adjustment of the strip.

Still a further object is to provide a stop strip having a groove on its face which engages a jamb, one side of the groove being adapted to engage 25 a bead or other projection on the jamb and the groove being entirely concealed when the stop strip is in applied position on the jamb.

Still a further object is to provide a bead and groove connection between stop strips and side 30 jambs and a rabbeted connection between a stop strip and a head jamb, so that after the head and side jambs are assembled, the stop strips can be applied to the side jambs and the stop strip can then be applied to the head jamb.

35 With these and other objects in view my invention consists in the construction, arrangement and combination of the various parts of my device, whereby the objects contemplated are attained, as hereinafter more fully set forth, pointed 40 out in my claims, and illustrated in the accompanying drawing, in which:

Figure 1 is a horizontal sectional view through the side jamb of a window, showing a liner strip applied thereto and the frame built into a 45 masonry wall.

Figure 2 is a similar sectional view showing the frame in a brick veneer wall.

Figure 3 is a similar sectional view showing an extra thick masonry wall with a subjamb replacing 50 the liner strip of Figures 1 and 2.

Figure 4 is a sectional view somewhat similar to Figure 1, showing another type of liner strip and showing a stop strip applied to the window jamb.

Figure 5 is a sectional view through a head 55 jamb of a window frame of the type shown in Figure 4, illustrating the liner strip and stop strip applied thereto; and

Figure 6 is a perspective view of a portion of a side jamb, a liner strip and a stop strip.

60 Referring to Figure 1, a side jamb is indicated

at 10. The inner edge of the side jamb 10 is rabbeted as indicated at 12. A liner strip A has a tongue 14 to engage the rabbet 12.

It will be noted that the surface 16 of the liner strip A is shorter than the surface 18 of the 65 jamb 10. This provides a shoulder at 20. In order to make the shoulder 20 in the form of a bead 22, the jamb 10 is depressed at 24. Thus the top of the head 22 does not project beyond the inner surface of the jamb 10 so that the jamb can 70 be more readily machine formed and thinner lumber may be used to form it.

The liner strip A is provided with a groove 26 and a flange 28. The groove 26 is adapted to receive lath 30 and plaster 32 of a wall covering 75 of the wall in which the jamb 10 is mounted. The flange 28 overlaps the lath or other covering 30.

It will be noted that the liner strip A may be used with masonry, as shown in Figure 1, studding being shown at 34 and a furring strip at 36. 80 The liner strip A may also be used in a brick veneer wall, as shown in Figure 2. The brick veneer is shown at 38 and furring strips, insulation or the like 40 may be interposed between the studding 42 and the brick veneer so that the 85 jamb 10 actually sets farther out with respect to the studding than it does in Figure 1. In Figure 2, lath 44 projects into the groove 26 of the liner strip A and the inner wall is faced with plaster 46.

As shown in Figure 3, where extra thick walls, such as of masonry are used, a subjamb or jamb extension 48 may replace the liner strip A. The subjamb 48 has a tongue 14a and a surface 16a corresponding to the tongue 14 and surface 16 95 of the liner strip A. Thus the bead 22 projects and forms a shoulder 20, the same as in Figures 1 and 2.

An inspection of Figure 4 makes it obvious that the shoulder 20 is adapted for limiting the 100 adjustment of an adjustable stop B toward a window sash 50, or toward the center of the jamb 10. The stop B has a groove 52 wider than the bead 22 so as to permit adjustment of the stop strip toward or away from the sash 50, but its 105 adjustment toward the sash is positively limited by the bead. Adjustment is made possible by securing the stop to the jamb 10 with screws 54 extending through enlarged openings 56 of the stop strip B.

In Figure 4 and also Figure 5, a liner strip A' is illustrated for a narrower wall, such as one of siding or shingle type. The strip A' has a tongue 14b and an edge 16b corresponding to these parts in Figure 1, but the strip is much narrower and the groove 26 is eliminated. The flange 28, however, is retained and the tongue 14b is made narrow enough to provide a groove, the sides of which are indicated at 58 and 60 and the bottom at 62.

65 The side 58 is formed by the rear edge of the 120

jamb 10. In Figure 5, I have illustrated a head jamb 10a with the liner strip A' associated therewith. The head jamb, however, does not have a bead 22, but instead has a rabbet 64. A stop strip B' (which may or may not be grooved like the strip B) engages the rabbet 64 to limit the adjustment of the stop strip toward the center of the jamb 10a, adjustment being retained by screws 54a through enlarged openings 56. The rabbet is used on the head jamb because it simplifies machining and facilitates application of the liners. If a rib were formed on the head jamb it would either have to be cut off at its ends adjoining the side jambs or the top ends of the liners on the side jambs would have to be notched to fit over the rib.

The liner strip A or A' provides additional nailing surface for the trim 66 as well as providing for coaction of the inner wall covering with the jamb 10 (the liner strip being a portion of the jamb when secured thereto). It was found in practice that the mechanic or carpenter in applying the stop strips B would set them too close to the sash 50 with the result that the sash 25 would not slide easily. The shoulder 20 of the bead 22 engaging one side of the groove 52 therefore predetermines the amount of channel clearance between the stop B and the center stop 68 (see Figure 4) of the window frame so that 30 the sash will slide easily at all times and in all positions of adjustment of the stop strips.

The groove 52 being wider than the bead 22, however, permits adjustment of the stop away from the sash, if desired. The stop B having a groove 52 rather than a projection of any kind makes it possible to easily sand the stop strip at the factory.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

45 I claim as my invention:

1. In a frame construction, jams, stop strips adjustably applied to the faces only of said jambs, said stop strips having double sided grooves therein intermediate the edges thereof and extending 50 from end to end thereof, said grooves being entirely concealed when said stop strips are in applied position.

2. A window frame having side and head jambs, stops applied on the faces of said jambs, a sash 55 to slide between said stops, one of said stops being adjustable to vary the distance between it and the other of said stops and thereby vary the width of the channel in which said sash slides, the jambs and the adjustable stop having formed faces to 60 abut each other to positively limit adjustment of the adjustable stop toward the sash.

3. In a frame construction, a jamb and a liner strip arranged edge to edge, trim applied to the inner edge of said liner strip, a shoulder formed 65 between said jamb and said liner strip by offsetting the inner face of said liner strip outwardly relative to the inner face of the portion of the jamb adjacent said liner strip, said jamb having a depression in its inner face adjacent said shoulder.

4. In a frame construction, a jamb and a liner strip arranged edge to edge, trim applied to the inner edge of said liner strip, a shoulder formed 70 between said jamb and said liner strip by offset-

ting the inner face of said liner strip outwardly relative to the inner face of the portion of the jamb adjacent said liner strip, said jamb having a depression in its inner face adjacent said shoulder and a stop strip having a groove to receive the resultant bead formed on said jamb and projecting from the face thereof with said shoulder constituting one of its sides.

5. In a frame construction, a jamb comprising a jamb member and a liner strip joined together edge to edge and a groove in the outer face of said liner strip for receiving the end of a wall covering on a wall in which said frame is set. 80

6. In a frame construction, a jamb having a rabbeted rear edge, a liner strip having a tongue fitted into said rabbet, said tongue being narrower than said rabbet whereby to provide a shoulder for a wall covering to engage and said liner strip having a flange for overlapping such wall covering. 90

7. In a frame construction, a jamb having a rabbeted rear edge, a liner strip having a tongue fitted into said rabbet and a groove formed in said liner strip to receive the end of a wall covering on a wall in which said frame is inserted, said liner strip having a flange for overlapping such wall covering. 95

8. In a window frame construction, a jamb, a liner strip forming an inward extension thereof and offset therefrom, an inside stop applied on 105 said jamb and said liner strip, said stop having parallel front and rear faces, a groove formed in near central position in the rear face thereof and a rib formed on said jamb along the edge thereof adjacent said liner strip to coact with said groove 110 to provide limited lateral adjustment of said stop relative to said jamb and said liner strip, the face of said liner strip adjacent said jamb engaging the face of said stop along one side of said groove.

9. In a window frame construction, a jamb, an 115 inside stop applied thereon, said stop having parallel front and rear faces, a groove formed in the rear face thereof and a rib formed on said jamb to coact with said groove to provide limited lateral adjustment of said stop relative to said jamb. 120

10. In a window frame construction, a jamb having on its inside face near its inner edge, a longitudinal rib extending from uni-planar surfaces at the two sides of said rib and a stop formed to straddle said rib for limited side adjustment of 125 the stop relative to the jamb.

11. In a window frame construction having a jamb and a stop, said jamb having a rib and said stop having a groove coacting therewith and wider than said rib to provide definite limits to 130 lateral adjustment of the stop relative to the jamb, the surfaces of the jamb adjacent the rib being substantially uni-planar and the surfaces of the stop adjacent the groove being substantially uni-planar. 135

12. In a window frame construction having a jamb, a liner strip forming an extension thereof and offset therefrom and a stop, said jamb having a rib adjacent the edge of said liner strip when abutting the edge of said jamb and said 140 stop having a groove coacting therewith and wider than said rib to provide definite limits to lateral adjustment of the stop relative to the jamb, the surfaces of the jamb and the liner strip adjacent the rib being substantially uni-planar 145 and the surfaces of the stop adjacent the groove being substantially uni-planar.
